UNITED STATES PATENT OFFICE.

HOWARD A. DUDLEY, OF HAGERSTOWN, MARYLAND.

TYPOGRAPHY.

Application filed December 29, 1922. Serial No. 609,702.

To all whom it may concern:

Be it known that I, HOWARD A. DUDLEY, a citizen of the United States, residing at Hagerstown, in the county of Washington 5 and State of Maryland, have invented certain new and useful Improvements in Typography, of which the following is a specification.

The present invention relates to improvements in typography and more particularly to the printing elements used and the means for handling and assembling these printing elements, incident to the making of the printing plates or forms from which printing is to be done. The primary object of the invention is to provide a novel and improved printing plate or form which will be a substitute for and will possess substantial advantages over electrotype plates which have been heretofore used generally for book printing and for similar classes of printing, the printing plates or forms, according to the present invention, being capable of production at much less expense than electrotype 20 and having the characteristics that they enable corrections to be easily, quickly and inexpensively made and the plates or forms can be made to readily accommodate cuts or similar insertions, although the printing plates or forms, according to the present invention, can be mounted on the same boards as heretofore used for the mounting of electrotype plates.

Another object of the invention is to provide a novel and improved galley to hold the assembled printing elements preliminarily to the making up of the printing plates therefrom, the galley being so constructed that corrections or substitutions of printing elements may be made easily and quickly and spilling of the printing elements from the galley is avoided.

To these and other ends, the invention consists in certain improvements and combinations and arrangements of parts, all as will be hereinafter more fully described, the features of novelty being pointed out particularly in the claims at the end of the specification.

50 In the accompanying drawings:—

Figure 1 is a face view of a printing plate embodying the present invention, the plate being shown mounted on a board similar to those used for mounting electrotype plates preparatory to printing therefrom;

55 Figure 2 represents a transverse section

through the printing plate and its mounting, the section being taken on the line 2—2 of Figure 1;

Figure 3 is a perspective view of a holder 60 and some of the printing elements used in making up the printing plate, this figure showing how one printing element can be removed and another printing element substituted;

65 Figure 4 is a face view of a galley adapted to hold the printing elements, the same being constructed in accordance with the present invention;

Figure 5 is a face view of a double-column 70 printing plate embodying the invention;

Figure 6 represents a cross section on the line 6—6, Figure 5, and

75 Figure 7 represents a cross section through a portion of a double-column printing plate which is shown in perspective, illustrating a modification of the construction shown in Figure 5.

Similar parts are designated by the same reference characters in the several views.

80 The present invention is applicable to all instances where printing is to be done from a printing plate or form made up of a number of printing elements, it being particularly suitable for use in those instances where electrotype plates have been required, as for instance, in book printing where a very large number of matrices are to be made. The preferred embodiment of the invention will be hereinafter set forth in 85 conjunction with the accompanying drawings, but it is to be understood that the invention is not restricted to this particular embodiment, as equivalent embodiments are contemplated and these will be included 90 within the scope of the claims.

95 According to the present invention, the matter to be printed is prepared in the form of printing elements, these printing elements consisting of type bars 1 which may be cast or produced in any suitable way. 100 These type bars are shallow in height, they preferably having a height equal to the height or thickness of the usual unmounted electrotype plate. The thickness of the type bars, of course, will vary according to the size of the type used. The bottom or foot 105 of the type bar is preferably flat and it is parallel with its top, the latter bearing the type face 2 which is similar to that produced 110 on the printing slugs as made by typographical machines of the well known linotype

class. The two sides 3 and 4 of the type bar are parallel and preferably smooth or like the sides of printing slugs or type bars as made by machines of the linotype class. The 5 ends of the type bar are bevelled, as at 5, for a purpose which will hereinafter appear. These type bars will bear the matter to be printed in the form of lines, as is the case with the printing slugs or type bars as made 10 by machines of the linotype class, and they are assembled in regular order, preferably in a galley which is adapted to hold them in proper order until they are made up in book form and otherwise prepared for printing therefrom. The present invention provides a novel form of galley for the holding of the type bars, this galley being preferably constructed substantially as shown in Figure 4. As there shown, the galley comprises 15 a flat sheet 6 of metal or other suitable material which provides a backing or surface on which the feet or bottoms of the type bars may rest on a common level, this sheet being made of any suitable length and having 20 its longitudinal edges bent up and turned inwardly, so as to provide upwardly converging flanges 7 which overlie the flat body portion 6 of the galley. One end of the galley is closed by bending up its base or 25 body portion to form an upstanding flange 8 which stands preferably at a perpendicular to the flat body portion 6 of the galley, and the other end of the galley is closed by bending up the adjacent edge of the body 30 portion 6 and turning this edge inwardly at an incline which may correspond to the inclination of the longitudinal flanges 7, an end flange 9 being thus formed. One of the longitudinal flanges 7 is recessed or cut 35 away, as at 10, for a suitable distance from the end flange 9, for a purpose which will presently appear. The galley is of a width corresponding with the length of the type bars or other printing elements which are 40 in use, and the type bars are introduced into the galley, in the proper order, either by placing them in the galley while in a diagonal position, as for example, as indicated in Figure 3 or by introducing the type 45 bars at the bottom of the galley through the recess 10 and then pushing the type bars upwardly. In either case, when the type bars are in proper position in the galley, their bevelled ends 5 will fit beneath the 50 longitudinal flanges 7 and these flanges will retain the type bars on a common level and they will prevent dislocation of the type bars from the galley. It is to be understood 55 that leads, rules and other blanking-out elements are to be provided for use in connection with the printing bars. For example, 60 11 may designate a rule which is relatively thin and is type-high, this rule having a configuration similar to that of the type bars, 65 including the bevels at the ends to cooperate with the longitudinal retaining flanges of the galley. Also, leads 12 of various thicknesses corresponding to the various point-sizes, may be provided and used in conjunction with the type bars, in order that the 70 latter may be made up properly for printing and to also enable the forms prepared from these type bars to be properly blanked out. These leads of various thicknesses or point-sizes are of less height than the type 75 bars, they being preferably quad-high. The leads of the greater thicknesses may be introduced through the recess or cut-away portion 10. A key or retaining element 13 is 80 preferably provided for each galley, the key being inserted after the galley has been filled with the type bars and leads or other blanking-out materials and the key then serving to retain the elements within the galley. The key, as shown, has bevelled ends 14 and also 85 a bevelled side 15, the latter being adapted to fit beneath the end flange 9 of the galley and allowing the key to be introduced into locking position by endwise movement through the recess 10. The engagement of 90 one of the longitudinal flanges 7 with the bevel on one end of the key and the engagement of the end flange 9 with the side flange of the key, prevent dislocation of the key from the galley, removal of the key being 95 effected by withdrawing it longitudinally through the recess 10. A galley constructed as described enables the printing elements and also rules, leads or blanking-out materials associated therewith to be retained 100 in proper relation without danger of spilling, but corrections or changes can be made with respect to the printing elements by removing the key, then pushing downwardly in the galley all of the matter immediately 105 below the line or type bar which is to be changed, it being then possible for the latter type bar to be brought into a diagonal position which will free one of its bevelled ends from the adjacent longitudinal flange 110 of the galley, so that such type bar can be removed, and another type bar may be substituted, the matter below the substitute type bar being restored to its former position and when the key is re-inserted, all of the matter 115 contained in the galley is locked.

The type bars and the rules, leads or blanking-out material are removed from the galley and placed in holders in preparing 120 the printing plates or forms from which the impressions are to be made. For example, these holders may be adapted for the preparation of printing plates or forms of book size. Figure 3 shows an example of a holder for the preparation of a printing plate or form of book size. It comprises a body 16 which is flat and may be composed of sheet metal or other suitable material. The longitudinal edges of the body 125 of the holder are bent up and turned in- 130

wardly to form a pair of parallel flanges 17 which are inclined in a direction upwardly and inwardly and they overlie the flat body portion of the holder. The width 5 of the holder corresponds to the length of the type bars with which it is to be used and the longitudinal flanges 17 of the holder are adapted to receive the bevelled ends 5 of the type bars or the correspondingly bevelled ends of the rules, leads or blanking-out material beneath them. One end of the holder is closed by bending up the adjacent edge thereof to form a flange 18, this flange preferably abutting against 10 the upper ends of the longitudinal flanges 17 and being arranged perpendicularly or substantially so with respect to the flat body portion of the holder. The lower end of the holder is open to receive the printing bars 20 and the leads, rules or other blanking-out material, as well as electrotype or similar cuts, one of which is shown in Figure 1 and is designated 19. Where cuts or the like are used, they will be made of a width corresponding 25 to the width of the holder in which they are to be placed, and the ends of the cut will be bevelled to correspond with the bevelled ends of the type bars. A blanking out member 20 may be placed in 30 the bottom of the holder, this blanking-out member having bevelled ends corresponding with those of the type bars and also a bevelled side 21 for a purpose that will hereinafter appear. When it is desirable or necessary 35 to make a change or correction in the printing plate or form, it is only necessary to shift the type bars and other matter below the line to be changed or corrected downwardly, so as to provide sufficient space 40 for the type bars requiring change to be twisted or brought into a diagonal position, as is shown in Figure 3, whereupon such type bar can be easily and quickly removed from the holder and another type bar 45 substituted, after which the type bars and other matter can be returned to their former position in the holder. The holder, together with the type bars and other elements contained therein and made up as desired, is 50 placed on a Wesel board like that used for the mounting of electrotypes, or upon any other suitable mounting. In Figures 1 and 2, a printing plate or form embodying the present invention is shown mounted on a 55 Wesel board, it being understood that the height of the type bars from the top of their printing surface to the bottom of the holder is substantially equal to the height or thickness of the ordinary electrotype plate. The 60 Wesel board 22 has a pair of inwardly inclined flanges 23 and 24 which overlie its type surface 25, these flanges being arranged one on the top edge and the other on one of the side edges of the board and 65 corresponding in inclination with that of

the longitudinal flanges 17 of the holder. Opposite to the flanges 23 and 24 are located screw clamps 26 which may be operated to grip the longitudinal flange 17 of the holder opposite to the flange engaged by the flange 24 and to engage the bevelled surface 21 on the blanking-out element 20 which is in the end of the holder. The holder containing the printing elements and their associated elements rests flatwise on the top surface 25 of the board and setting up of the clamps 26 locks the holder to the board and also locks the printing and other elements in proper relation within the holder, one of the clamps 26 acting in a direction endwise of 70 the holder and in a direction to compress the printing and other elements contained therein, a printing plate or form being thus provided which may be placed in a press like an ordinary electrotype plate and the printed impressions obtained directly therefrom. If desired, each holder containing the printing elements and the elements associated therewith in final form ready for printing may be provided with a relatively hard or 75 wear-resisting surface, as by immersing the holder in an electroplating bath and depositing nickel or other suitable metal on the printing faces of the type bars. 80

It is to be understood that the invention 85 is applicable to holders or lock-ups which provide for two or more columns of printing matter in the printing plate. For example, Figures 5, 6 and 7 illustrate the invention applied to double-column holders or lock-ups, the holder or lock-up 16^a having its flat backing made sufficiently wide to accommodate the increased number of columns, and having the overlying flanges 17^a at its vertical edges to form ledges to receive beneath them and thus retain the outer bevelled ends 5 of the printing elements 1, as described in connection with the single column form of holder shown in Figure 3, and an intermediate member 27 is provided 100 which is adapted to extend vertically across the face of the backing of the holder midway between and parallel with the side member having its under side bevelled oppositely or convergently toward the face of the backing of the holder to form flanges or ledges 28 which overlie the face of the holder and are adapted to receive beneath them the bevelled proximate ends 5 of the printing elements contained in the adjacent columns, thus cooperating with the flanges or ledges 17^a to retain the printing elements in place. The intermediate member may be held in proper position in the holder in 105 different ways. For example, in Figures 5 and 6, the upper end of the member enters and is held in a notch 29 formed in the under side of a blanking-out element 30, the latter being removably inserted in the holder and being held in place by the top flange 110 115 120 125 130

or overlying ledge 31 and the overhanging flanges or ledges 17^a, the top edge and ends of the element 30 being suitably bevelled to fit beneath these flanges or ledges. Similarly, the lower end of the intermediate member may be inserted into a notch formed in the under side of a blanking-out element 32, the ends of the element being bevelled to fit beneath the overhanging flanges or ledges 17^a. Another mode of holding the intermediate member 27 in place in the holder may consist in welding or otherwise securing the lower edge of this member, as at 33 in Figure 7, to the face of the flat backing 15 of the holder, the member in this instance being permanently secured to and forming a part of the holder. In each instance, however, the printing element, including the rules, leads and blanking-out elements may 20 be assembled and held in the holder or lock-up to make up the printing plate in substantially the same manner as described in connection with the single-column printing plate. It will be understood that different 25 numbers of intermediate members 27 may be fitted to each holder to adapt the latter to different numbers of columns and that by using elements like those designated 30 and 32, but containing different numbers of appropriately located notches in their undersides, the holder may be made to accommodate 30 different numbers and widths of columns.

Type bars and leads, rules and blanking-out or other elements to be associated therewith in making up printing plates or forms, in accordance with the present invention, are capable of assembly in galleys or holders with facility, and after assembly, they 35 can be easily and quickly shifted relatively to one another and to the galley and the holder to enable corrections or changes to be made easily, quickly and inexpensively,

thus possessing substantial advantages over the ordinary electrotype plates and, moreover, the printing plates embodying the present invention can be produced at less cost than electrotype plates, they can be used as satisfactory substitutes therefor, and they require no greater space when stored either in galleys or in the holders when detached from the mounting boards. By electrotyping nickle or other relatively hard metal on the type faces of the printing plate, great durability can be attained.

I claim as my invention:—

1. A holder for a composed printing surface made up of a plurality of printing elements, comprising a flat backing against which the bottoms of the printing elements are adapted to rest flatwise throughout their lengths, and inturned retaining flanges along the opposite edges of the backing beneath which the ends of the printing elements project, and means located wholly below the plane of the printing faces of the printing elements in the holder for confining said elements in composed relation.

2. A printing plate adapted for use as a substitute for an electro-type plate, comprising a holder embodying a flat backing, in-turned longitudinal retaining flanges which overlie the face of the backing, and a fixed flange which closes one end of the holder, a composed printing surface comprising a plurality of printing elements resting against the flat backing and having their ends shaped to fit beneath the in-turned retaining flanges, and means located wholly below the plane of the printing faces of said elements for locking up the latter against said end flange.

In testimony whereof I have hereunto set my hand.

HOWARD A. DUDLEY.
